SAFE DISPENSING CONTAINER

Jacob G. Heim, San Gabriel, Calif., assignor to
 The Calpat Corporation, Los Angeles, Calif., a
 corporation of California

Application July 16, 1948, Serial No. 39,149

2 Claims. (Cl. 43—121)

1

This invention refers to improvements in safety dispensing containers and more particularly to a dispensing container of the type which is adapted to act as a container for noxious or poisonous fluids and which is so designed that the inadvertent or accidental removal of the fluid contained therein may be prevented.

A specific application for my invention lies in containers which are adapted to permit poisonous fluids to be dispensed to crawling insects such as ants and which are adapted to be deposited about the house or the garden in positions in which they are readily accessible to children and household pets. It is also within the concept of my invention to provide a container for noxious or poisonous fluids which will prevent the inadvertent drainage of a container containing such fluid should an individual attempt to drain the container thinking that the contents thereof are nonpoisonous or beneficial.

As indicated above, it is the custom to dispose containers of noxious or poisonous fluids about the garden or the house which are adapted to permit the entry of insects thereinto to facilitate the poisoning of the insects and to rid the house or garden thereof. Numerous accidents to both children and household pets have occurred as the result of the use of such containers. Quite frequently children, happening upon such containers, will pick them up out of curiosity and drink their poisonous contents with extremely harmful results.

It is, therefore, a primary object of my invention to provide a container for poisonous fluids which will permit the ready dispensing of such fluids to the insects whose eradication is desired but which will not permit the contents thereof to be drunk by a child, another individual or a household pet.

There are in use at the present time such containers adapted to dispense poisonous fluids automatically which have embodied therein wick means having one end deposited in the fluid within the container and the other end protruding therefrom to render the poisonous liquid accessible to the insects whose destruction is desired.

It is another object of my invention to provide a container for poisonous fluids which has no protruding wick-like elements embodied therein, but which will incorporate dispensing means to prevent a child from inserting a stick or other element in the container and from withdrawing from the container any of the poisonous fluid contained therein upon the stick.

2

One of the greatest hazards inherent in the construction of poisonous fluid-dispensing containers is the fact that most of those in use at the present time have filling means or openings which are provided with caps susceptible of easy removal by a child who may stumble upon the container.

It is another object of my invention to provide a container adapted to dispense poisonous fluids which has embodied therein an automatic, inaccessible closure means which will automatically close off the access to the interior of the container and the fluid therein when the cap sealing the filling opening of the container is removed.

Containers of the conventional type are readily discernible by their size and shape to a child, and it is within the scope of my invention to provide a container which has such a configuration that it will readily simulate a piece of scrap lumber or any other similar object which is ordinarily found lying about the garden or within the house and of such a nature as not to excite the curiosity of a child.

It is a further object of my invention to provide a container adapted to dispense poisonous fluids which is so shaped and constructed that whatever the position may be in which it is disposed upon the surface of the ground or upon the surface of areas within the house, it will nevertheless assume a position in which the entry to the dispensing means embodied in the container is readily accessible to insects crawling upon the ground or the surface of the object upon which the container is disposed.

It is generally the object of my invention to provide a container for noxious or poisonous fluids which will permit the ready distribution of poisonous fluids to the insects for whose consumption they are intended, but which will nevertheless prevent the inadvertent drainage of the fluids by children who may happen upon the container.

Other objects and advantages of the invention will be apparent from a consultation of the following specification and the accompanying drawings, which is for the purpose of illustration only, and in which:

Fig. 1 is a perspective view of a preferred embodiment of my invention;

Fig. 2 is a transverse sectional view taken on broken line 2—2 of Fig. 1;

Fig. 3 is a vertical sectional view taken on line 3—3 of Fig. 1;

Fig. 4 is a longitudinal sectional view of another embodiment of my invention;

Fig. 5 is a vertical sectional view of still another embodiment of my invention;

Fig. 6 is a bottom plan view taken along line 6—6 of Fig. 5 and showing the manner in which the automatically actuated closure means incorporated within the embodiment of my invention shown in Fig. 5 is distended by the insertion therein of the dispensing tube; and

Fig. 7 is a fragmentary detail showing the manner in which the automatic closure means of Fig. 6 contracts when the dispensing tube is withdrawn therefrom to prevent the inadvertent dispensing of nocuous fluids from the container.

Referring to Figs. 1, 2 and 3 of the drawing, I show a preferred embodiment of my invention which includes a dispensing container 10 having side walls 11, 12 and 13 and being formed in the general configuration of a triangle for a purpose which will be explained in greater detail below. A forward wall 15 joins the side walls 11, 12 and 13 of the container and is provided with an elongated filling opening 17 which renders accessible a fluid containing chamber 18 adapted to receive a predetermined amount of nocuous or poisonous fluid 19 therein.

The dispensing container 10 is also provided with a rear wall 16 which has a dispensing opening 20 formed therein adapted to permit access by the insects whose destruction is desired to the interior of the chamber 18. A dispensing tube 21 having an entry port 22 and an exit port 23 has the entry port 22 disposed contiguously to the dispensing opening 20 formed in the rear wall 16 of the container 10.

Thus, as can be seen from Figs. 2 and 3 of the drawing, the container 10 may be filled with nocuous or poisonous fluids through the medium of the filling opening 17 which is provided with a securely fastened closure 24 which cannot be readily removed from the filling opening 17. The amount of fluid deposited in the fluid chamber 18 is such that, when the container 10 is disposed upon any of the sides 11, 12 or 13, the fluid level will lie below the peripheral area of the dispensing tube 21, and when the container is stood upon end the fluid level will lie below the exit port 23 of the dispensing tube 21. The exit port 23 of the dispensing tube 21 is of substantially smaller diameter than the diameter of the entry port 22 so that, should a child pick up the container and shake it, the inadvertent dispensing of fluid through the exit port 23 is precluded since the dimensions of the exit port 23 are so small that the shaking of the container 10 will not permit the dispensing of fluid therefrom.

The exterior of the container 10 is provided with an incised or protuberant fluid level or gage line 26 which, if the container 10 is formed of translucent material, will enable the person filling the container through the filling opening 17 to readily determine when the container has been sufficiently filled with poisonous fluid. In addition, the exterior of the container 10 is provided with a pattern or design 27 which is adapted to render the container 10 inconspicuous and not readily ascertainable by a child. For instance, in the embodiment shown, the external surfaces of the container 10 have been provided with a wood grain finish which renders the container exceedingly inconspicuous and gives it the appearance of a piece of scrap lumber. Thus, the container is not readily seen by a child, and since it appears to be a familiar

object, there is no motivation for a child to pick up the container 10 for further investigation.

A triangular extension 28 of the container 10 is formed upon and integrally with the rear wall 16 thereof and is provided with a wedge-shaped opening 29, the apex 30 of which surrounds the dispensing opening 20 formed in the rear wall 16 of the container 10. The sides of the wedge-shaped opening 29 constitute a plurality of inclined ramps 31 which are a means of access to the dispensing opening 20 for insects whose destruction and eradication by the poisonous fluid 19 contained within the chamber 18 is intended.

Due to the triangular configuration of the container 10 and due to the wedge-shaped opening 29 provided in the triangular extension 28, the lower end of one of the two ramps 31 provided by the side walls of the wedge-shaped opening 29 will always be disposed close to the surface upon which the container 10 is placed, thus facilitating the easy access of undesirable insects to the dispensing opening 20. As can be readily seen from the drawing, the wedge-shaped opening is disposed in an angular relationship to the axis of the container 10. When the insects enter the dispensing opening 20 they pass through the entry port 22 of the dispensing tube 21 and then traverse the length of the dispensing tube 21 which they are permitted to leave through the exit port 23 of the tube so that they may contact the poisonous fluid 19. The dispensing tube 21 has its axis substantially coaxial with the axis of the filling opening and the axis of the passage provided by the triangular extension 28 is disposed in angular relationship to the axis of the dispensing tube.

As can be readily conceived, should a child, 40 out of curiosity, pick up the dispensing container from the ground or the surface upon which it is disposed, he will first attempt to remove the securely fixed cap 24 from the filling opening 17. Failing to do this, due to the secure fixation of the cap, he will then attempt to remove 45 some of the fluid in the chamber 18 of the container by shaking the container up and down. Due to the small exit port 23 of the dispensing tube 21, he will fail in this attempt. If any further attempts to obtain the poisonous fluid 50 from the container 10 are made, they will probably lie in the direction of inserting a stick or similar elongated object into the passage formed by the wedge-shaped opening 29 in the triangular-shaped extension 28. Since the wedge-shaped opening or passage 29 is disposed in angular relationship to the dispensing opening 20 and the appended dispensing tube 21, the child is unable 55 to insert the stick or similar element into the chamber 18 and is thus prevented from withdrawing any poisonous fluid therefrom. In this manner, the inadvertent and accidental poisoning of children by imbibing the poisonous contents of such containers is avoided by my invention, but the container is, nevertheless, just as effective in attaining its primary purpose of dispensing poisonous fluids to insects whose eradication is desired.

Another embodiment of my invention is shown 60 in Fig. 4 of the drawing, exemplified by a container 33 which incorporates an inner vessel 34 which is concealed in an outer concealing housing 35 formed of wood or analogous material and adapted to prevent the easy discernment of the 65 container 33 by children when the container 33

is disposed about the garden or the house. The inner vessel 34 provides a fluid-containing chamber 36 which is adapted to receive a predetermined amount of poisonous fluid through a filling opening 37 which may be readily closed and sealed by closure means 38 threadedly engaged with the external portions of the filling openings or otherwise suitably secured thereto. The inner vessel 34 is provided with a dispensing opening 39 through the medium of the closure means 38, and there is attached to the closure means contiguous to the dispensing opening 39 a dispensing tube 40 whose axis is substantially coaxial with the axis of the container 33.

The dispensing tube 40 is provided with an entry port 41 and an exit port 42, the exit port 42 being of somewhat smaller diameter than the entry port 41 to prevent fluid from being ejected through the dispensing tube 40 when the container 33 is shaken by a child in an attempt to dislodge the contents of the fluid-containing chamber 36 therefrom. Although the main portion of the dispensing tube 40 has its axis coaxial with the axis of the container 33, the dispensing tube 40 is formed with an off-struck, integral portion 43. By the provision of the integral, off-struck portion 43 in the body of the dispensing tube 40, the possibility that a child may be able to inject a foreign body into the fluid-containing chamber 36 is eliminated and the child is unable to withdraw fluid from the fluid-containing chamber 36 by such an expedient.

Formed in that portion of the outer concealing housing 35 contiguous to the dispensing opening 39 in the closure 38 is a plurality of passages 44 provided by means of orifices 45 formed in the body of the outer concealing housing 35 and arranged with their axes angularly disposed to the axes of the dispensing tube 40 and the container 33. When the container 33 is disposed upon the surface of the ground insects are enabled to enter the fluid-containing chamber 36 through the medium of the passages 44, the dispensing opening 39 and the dispensing tube 40. However, due to the fact that the fluid level within the fluid-containing chamber 36 is regulated in such a manner that fluid cannot be withdrawn through the dispensing tube 40, a child who may pick up the container 33 is unable to drain the poisonous fluid therefrom.

In Figs. 5, 6 and 7 of the drawing is shown another embodiment of my invention, which is exemplified by a container 47 adapted to be utilized in the dispensing of poisonous or noxious fluid to undesired insects in a manner analogous to that in which the previously described embodiments of my invention are adapted to dispense such fluid. The container 47 provides a fluid-containing chamber 48 to which access may be had for filling purposes through the medium of a filling opening 49 which is designed to be securely closed by means of a closure member 50.

The closure member 50 is provided with a threaded mock aperture 51 in its upper portion so that a child who picks up the container and turns it upside down in an attempt to remove its contents may be deceived into believing that the container is empty. The closure means 50 also provides a dispensing opening 52 which is designed to permit undesirable insects to have access to the contents of the fluid-containing chamber 48. Mounted upon the underside of the closure 50 or formed integrally therewith in communication with the dispensing opening 52 is

a dispensing tube 53 through which access may be had to the contents of the fluid-containing chamber 48 by insects. Also provided in the body of the closure 50 is a passage 54 which permits communication from the outside of the container to the dispensing opening 52 and the dispensing tube 53 by insects desiring to enter the interior of the container 47. The passage 54 has its axis disposed in angular relationship to the axis of the container 47 and the axes of the dispensing opening 52 and dispensing tube 53 to render it impossible for a child to insert a foreign body into the fluid-containing chamber 48 and to thus withdraw poisonous or noxious fluid therefrom.

While it is intended that the primary purpose of the container 47 be the automatic and safe dispensing therefrom of noxious or poisonous fluids to undesired insects, the container 47 is also provided with automatic closure means adapted to prevent the inadvertent removal therefrom of medicinal liquids which may be stored therein. To accomplish this purpose the container 47 is provided with a resilient closure means 55 which is disposed in the passage constituted by the filling opening 49 and which, in the present embodiment of the invention, is constituted by a rubber gland 56. Although the container is shown in the drawing as having a wick 57 provided in the dispensing tube 53, it is intended that the wick 57 not be provided with the dispensing tube 53 when the container 47 is utilized as a container for fluids, such as iodine, potassium permanganate, acidulous mixtures, and other fluids, designed to be applied externally but exceedingly harmful if taken internally by accident.

It is common knowledge that many serious accidents result from the inadvertent drainage of vessels containing poisonous or noxious fluids which are removed from a medicine cabinet and drained under the mistaken assumption that their contents are of a beneficial nature. Of course, it also happens that children having access to the contents of a medicine chest will frequently remove conventional closures from the vessels containing harmful fluids and drain the contents thereof. The container 47 is adapted to prevent the occurrence of such unfortunate accidents by providing the automatic resilient closure means 55 in the filling opening 49 of the container. When the container and its harmful contents are placed upon the shelf of a medicine cabinet, the closure 50 is removed from the filling opening and the dispensing tube 53 is thus withdrawn from the position in which it distends the resilient closure means 55. The mouth of the closure means 55 is automatically sealed upon the withdrawal of the dispensing tube 53 therefrom, and it is impossible to drain the poisonous fluid contained within the fluid-containing chamber 48 until the closure 50 is once again installed upon the container 47 and the dispensing tube 53 inserted through the closure means 55 to permit access to the noxious or poisonous contents of this chamber.

Should a child insert an object through the closure means 55, the closure means will serve to wipe it clean of poisonous fluid as it is withdrawn, so none will remain upon the inserted object. Of course, the filling opening 49 may also be closed by reversing the closure member 50 and threading the area thereof surrounding the mock aperture 51 upon the container 47.

The withdrawal of the closure means 50 from its relationship with the filling opening 49 will

cause the resilient closure means 55 to seal in the manner shown in Fig. 7 of the drawing. When reinserted into the filling opening 49, the dispensing tube 53 associated with the closure means 50 will cause the resilient closure means 55 to expand in the manner shown in Fig. 6 of the drawing. Therefore, when the closure means 50 is removed from the container 47, the contents of the fluid-containing chamber 48 are automatically sealed off and access thereto may only be had by re-installing the closure 50 upon the container 47.

By my invention I thus prevent the inadvertent drainage of the harmful and poisonous contents of vessels and eliminate the possibility that the accidental consumption of the contents of such vessels may take place.

In addition, I provide a container adapted to contain and dispense nocuous or poisonous fluids which is provided with dispensing means designed to prevent unauthorized access to said fluid by children, household pets or unauthorized individuals. The containers which are shown as embodiments of my invention may be easily and cheaply manufactured, are of durable and rugged construction and may be readily refilled when the fluid contained therein is exhausted.

Although I have shown and described herein preferred embodiments of my invention incorporating specific elements, I desired it to be understood that such embodiments have been shown for the purpose of illustrating the manner of construction and mode of operation of my invention; and I, therefore, do not intend that my invention be limited to the specific constructions and elements shown but prefer rather that it be accorded the full scope of the following claims.

I claim as my invention:

1. A vessel adapted to permit the safe dispensing of nocuous fluids including: a triangularly shaped housing having a fluid chamber formed therein and a dispensing opening in communication with said fluid chamber; a dispensing tube communicating with said chamber adapted to permit access to said fluid and having its axis substantially coincident with the axis of said chamber and having an entry port and an exit port, said entry port being juxtaposed to said

5 dispensing opening; and said housing having a passage in the bottom thereof communicating with said entry port to said dispensing tube, said passage being triangular in transverse cross section adjacent said fluid chamber, and wherein the closed apex of said passage is located adjacent said entry port.

2. A vessel adapted to permit the safe dispensing of nocuous fluids including: a triangularly shaped housing having a fluid chamber formed therein and a filling opening and a dispensing opening in communication with said fluid chamber; a closure securely sealing said filling opening; a dispensing tube communicating with said chamber adapted to permit access to said fluid and having its axis substantially coincident with the axis of said filling opening and having an entry port and an exit port, said entry port being juxtaposed to said dispensing opening; and 10 said housing having a passage in the bottom thereof communicating with said entry port to said dispensing tube, said passage being triangular in transverse cross section adjacent said fluid chamber, and wherein the closed apex of said passage is located adjacent said entry port.
